[57] **CLAIM**

The ornamental design for a head for a portable air blower for yard and lawn care, substantially as shown and described.

DESCRIPTION

FIG. 1 is a side elevational view of a head for a portable air blower for yard and lawn care showing our new design, in which broken lines are shown for illustrative purposes only and form no part of the claimed design; FIG. 2 is an enlarged elevational view thereof; FIG. 3 is an elevational view as seen from the opposite side;

FIG. 4 is a front elevational view thereof;

FIG. 5 is a rear elevational view thereof;

FIG. 6 is a top plan view thereof;

FIG. 7 is a bottom plan view thereof.

FIG. 1

FIG. 2

FIG. 3
